DESIGN FOR A LIGHTING FIXTURE

John S. Walsh, San Francisco, Calif.

Application July 26, 1948, Serial No. 147,780

Term of patent 14 years

(Cl. D48—23)

To all whom it may concern:

Be it known that I, John S. Walsh, a citizen of the United States of America, residing at 772 Francisco Street, San Francisco, California, have invented a new, original, and ornamental Design for Lighting Fixtures, of which the following is a specification, reference being had to the accompanying drawing, forming part thereof.

Fig. 1 is a view in perspective from below of a lighting fixture, showing my new design;

Fig. 2 is a view in side elevation;

Fig. 3 is a view in front elevation, and

Fig. 4 is a bottom plan view of the same.

I claim:

The ornamental design for a lighting fixture, substantially as shown.

JOHN S. WALSH.
